United States Patent Office.

SAMUEL E. HYNDMAN, OF MIDDLE TOWN, OHIO.

Letters Patent No. 64,225, dated April 30, 1867.

IMPROVEMENT IN WAGON-BRAKE.

The Schedule referred to in these Letters Patent and making part of the same.

TO ALL WHOM IT MAY CONCERN:

Be it known that I, SAMUEL E. HYNDMAN, of Middletown, in Butler county, in the State of Ohio, have invented a new and useful Improvement in Wagon-Brakes; and I do hereby declare that the following is a full and exact description thereof, reference being had to the accompanying drawings, and to the letters of reference marked thereon.

Figure 1 represents a top view of my invention as applied to a wagon.

Figure 2 is a vertical sectional view, taken at the line xx of fig. 1.

In the accompanying drawings, a indicates the axle-tree; b , the sand-board; $c c$ and $g g$, the hounds; $d d$, the hound-braces or sliders; h , the tongue-bolt; and i , the wagon-tongue.

My improved brake consists in the arrangement of two brake-levers ff , secured to the hounds $c c$ by the rear right-angular portion of the braces $d d$, which pass through the brake-levers ff and hounds $c c$ at o , and of rods $e e$, connecting the rear portion of the tongue-hounds $g g$ with the inner ends of the brake-levers ff . The tongue-bolt h , which connects the tongue-hounds $g g$ with the hounds $c c$, has its ends extending through the hounds $g g$, resting in slots rr , made in the hounds $c c$, the purpose of which will be herein explained. The rear ends of rods $e e$, connecting with the brakes ff , may be secured thereto by nuts and screws. The metal strap or plate p , fastened to the hounds $c c$, is provided with a bolt hole, through which the bolt s will freely pass, and enter into a hole in the rear end of the wagon-tongue. This bolt s (for the ordinary general use of the wagon) may hang suspended from a cord; but when it is desired to back the wagon without bringing the brakes into action the bolt s will be dropped in place.

The operation of my improved brake I will now describe. As the wagon progresses on ordinarily level ground, or when ascending an inclination, the brakes ff will be kept out of contact with the wheels by the action of drawing the load by the tongue, the double-trees being fastened thereto at the hole t ; but when the wagon is descending an inclination the act of holding back by the team will cause the tongue, with the hounds $g g$ and bolt h , to slide backwards, (the bolt h working freely with its ends in the slots rr ,) thereby thrusting the rods $e e$, which connect with the inner ends of the brakes, and causing the brakes to move around on the bolts, (consisting of the bent end of sliding-iron or brace d ,) which secure them to the hounds $c c$, thus bringing the short ends of levers ff in contact with the perimeter of the wheels $A A$. As soon, however, as the wagon again reaches the level ground the action of the team to draw the load will disengage the brake-levers with the wheels by sliding the tongue, with its hounds and bolt h , forward, the bolt resting against the forward ends of slots rr in the wagon-hounds $c c$. The act of the team in holding back from the end of the wagon-tongue, in the usual manner, will effectually bring the brakes ff into action; and the retarding power which they will exert will depend upon the width of the hounds between the wheels, because the fulcra of the levers ff , when brought near the wheels, will afford greater leverage, and diminish the power exerted by the team in holding back the load when descending an inclination. My invention is adapted to be used on wagons of ordinary construction, and involves very slight mechanical changes therein, the slots in the hounds for the bolt by which the wagon is drawn, the rods $e e$, and brake-levers ff constituting the essential features of my improvement. The cheapness and simplicity of the structure I deem to be a very important consideration. The bolt h , as before remarked, is intended to be inserted when it is desired to prevent the brakes from being brought into action, and therefore may be termed the lock or break-lock bolt.

I am aware that wagon-brakes operated by the team have been constructed; but I do not claim such a principle of operation irrespective of the mode of construction and arrangement.

Having fully described the construction and manner of using my improved wagon-brake, what I claim, and desire to secure by Letters Patent, is—

The brake-levers ff , rods $e e$, in combination with the slider-braces $d d$, hounds $c c$, and tongue i , sliding-bolt h , and lock-bolt s , when the parts are constructed, arranged, and operate in the manner and for the purpose specified.

Witness my hand this 28th day of January, 1867.

S. E. HYNDMAN.
